UNITED STATES PATENT OFFICE.

JOHN E. CONZELMAN, OF ST. LOUIS, MISSOURI, ASSIGNOR TO UNIT CONSTRUCTION COMPANY, OF ST. LOUIS, MISSOURI, A CORPORATION OF DELAWARE,

CONCRETE CONSTRUCTION.

1,045,520.

Specification of Letters Patent. Patented Nov. 26, 1912.

Original application filed April 14, 1910, Serial No. 555,354. Divided and this application filed June 5, 1911. Serial No. 631,279.

To all whom it may concern:

Be it known that I, JOHN E. CONZELMAN, a citizen of the United States, residing at the city of St. Louis, State of Missouri, 5 have invented certain new and useful Improvements in Concrete Construction, (divisional Case P,) of which the following is a specification.

This application is a division and continuation of one filed by me April 14, 1910, Serial No. 555,354.

This invention relates to certain new and useful improvements in concrete construction in which concrete girders are used to 15 support concrete slabs and are themselves supported by means of columns or uprights.

The object of this invention is to provide a rigid and unitary structure in which a supporting column or upright has means to support the girders, so that a space is left between the girder ends that rest upon the supporting means in order to form a seat for the base of a superimposed column with- 25 out the necessity of providing the girder ends with cut away portions, as heretofore.

The present invention further relates to means for connecting a supporting reinforced column with a superimposed reinforced column, so that continuity of the reinforcement is obtained between the columns.

In the drawings: Figure 1 is a view in perspective of the present invention, some of 35 the parts being broken away and in section, Fig. 2 is a top plan view, and Fig. 3 is a section on the line 3—3 of Fig. 2.

The girders 1, have their opposite sides formed with shoulders 2, on which the slabs 40 3 seat. The girder ends rest upon a cap 4 of a supporting column 7. Each corner of girder 1 is beveled so that, when the girder ends are placed on cap 4, each beveled corner fits against the similarly beveled corner 45 of an adjacent girder. When the girders are placed upon cap 4, in a manner as just described, a space 11 is left between the girder ends. The girders are preferably reinforced with flanges or ribs 12, 50 which extend downwardly on each side thereof. In addition spaced transverse reinforcing bars 13 are embedded in the girders near the top faces thereof. Bars 15 which extend transverse to the girders are

located near the bottoms thereof, while bars 55 16 extend longitudinally of the girders and have their ends projecting beyond the girder ends. Short bars 17 underlie bars 13, and project from the girder ends, the bars 17 being arranged to assist in taking up the 60 tensile stress obviously existing in the top surfaces of the parts of the girders that rest on cap 4. Bars 18 lie near the bottom surfaces of flanges 12, and some of said bars 18 bend upwardly and project from the girder 65 ends. Slabs 3 may either be flat or provided with flanges or ribs 20 formed on their under faces, the flanges in the latter instance seating on shoulders 2 of the beams.

The present invention relates particularly 70 to the employment of a metal column 27 which may be formed of angle bars 30, and diagonal braces 31, connecting the latter in the manner shown in the drawings, the metal column being embedded in the plastic column 75 7. The column 27 is preferably formed with such length that its top end extends over cap 4 to allow the lower or base end of a superimposed metal column 29 to be connected thereto by means of splice plates 32, or their 80 equivalent. Metal column 29 is constructed in a manner as just described in connection with metal column 27, the column 29 being embedded in a plastic column 19. For the purpose of supporting the girders 1, a structural steel cap is utilized which cap is composed of the brackets 33, that are fastened by any suitable means to column 27 in order to support the angle-irons 34, which extend entirely around column 27. The angle irons 90 34, are of a shape conforming to that of the cap 4, and extend into the latter so that their horizontal portions are flush with the top face of the cap 4. The brackets 33 are in the form of tapering plates whose ends are bent 95 at right angles and secured in any approved manner to the angle-irons 34 and to the metal column 27, the top edges of brackets 33 being flush with the top face of cap 4. Two brackets 33 are employed for each angle-iron, being arranged in the space between 100 the latter and the column 27.

In the practice of the present invention column 7 and cap 4 are formed around metal column 27 and the steel cap, the cap 4 being, 105 integral with column 7. The girder ends are then placed upon cap 4, their inner ends resting on angle-irons 34, and the slabs 3

are laid upon the shoulders 2 of the girders. Metal column 29 is then secured at its base to the upper projecting end of metal column 27, as above described, and a form is placed 5 around metal column 29 and is filled with plastic concrete, the latter entering the space 11, and fills the interior of metal column 29 and the projecting end of metal column 27, and not only forms the column 19, 10 and provides an enlarged base therefor but in addition unites cap 4 and the girder 1, integrally together, the column 19 being integral with the concrete which fills space 11. By resting the girders upon angle-irons 34, 15 their load is distributed to the steel cap, thereby dispensing with any other reinforcement for the column cap 4.

What is claimed is:

In concrete construction, a lower metal 20 column, a metal cap completely surrounding said column and located below the upper end thereof, a plastic column inclosing said metal column and having a cap that completely incloses the metal cap, the top face of the metal

cap being flush with the top face of the 25 plastic cap so as to be exposed, an upper metal column, means for connecting the upper metal column to the lower metal column, oppositely disposed girders having their inner ends directly seating on the exposed top 30 face of the metal cap and on the adjacent top face portions of the plastic cap and being spaced from the adjacent ends of the metal columns and said connecting means thereof to form a continuous space that encircles said 35 column ends and connecting means, a plastic column inclosing said upper column, and an enlarged base integral with said last named plastic column and completely filling said space defined by the top face of the cap, said 40 girder ends, the adjacent ends of the metal column, and said connecting means.

In testimony whereof I hereunto affix my signature in the presence of two witnesses.

JOHN E. CONZELMAN.
